UNITED STATES PATENT OFFICE.

CHARLES O. HASKELL, OF SAN FRANCISCO, CALIFORNIA.

RECIPROCATING PUMP.

Application filed August 5, 1922. Serial No. 579,877.

To all whom it may concern:

Be it known that I, CHARLES O. HASKELL, a citizen of the United States, residing at 637 Lake Street, San Francisco, in the 5 county of San Francisco, State of California, have invented a new and useful Reciprocating Pump, of which the following is a specification, in such full and clear terms as will enable those skilled in the art

10 to construct and use the same.

This invention relates to a pump, and its object is to produce a pump which is capable of throwing a steadier stream of water than the ordinary reciprocating pump can 15 throw, by reason of the provision it has for the production of two balancing air chambers within the pump which makes it more evenly operated than the ordinary reciprocating pump, and which cause a more uniform 20 form flow of the water therefrom.

Other objects of the invention will appear as the description proceeds.

An embodiment of the invention is shown in the accompanying drawings in which the 25 same reference numeral is applied to the same portion throughout, but I am aware that there may be modifications thereof.

Fig. 1 is a view partly in a vertical section of the complete pump.

30 Fig. 2 is a plan view of the complete pump.

Fig. 3 is a horizontal sectional view of the complete pump on the line 3—3.

35 Fig. 4 is a detail illustrating the manner of securing one of the gaskets inside the pump cylinder.

Fig. 5 is a vertical sectional view of a modified form of the pump in which the pump plunger consists of the tubular member 40 extending to the surface of the well, and which is balanced by the admission of air thereinto.

Fig. 6 is a plan view, in section, of the lower portion of the pump on the dotted line 45 6—6, Figure 5.

The numeral 1 indicates the suction pipe which is connected to the pump barrel 2 by means of the cap 3, said cap carrying two inwardly opening valves 4 and 5.

50 The pump barrel is closed at the top and has the discharge pipe 6, although, if the pump is to be used in a small, deep well, the discharge pipe 6 may extend straight up equally as well.

55 Within the lower portion of the cylinder 2 there is an annulus formed of an angle bar, as

shown at 7. This annulus is connected to the cylinder by means of suitable screws 8 to carry a packing gasket 9 which is secured thereto by means of the ring 10 and screws 11 (see Fig. 4).

Inside the upper portion of the cylinder there is a second cylinder 12, closed at the top. This cylinder is supported at a fixed distance from the top of the pump cylinder 2 by means of two rods 13 and 14, and said cylinder supports a transverse disc 15, by means of the two rods 16 and 17. These two rods pass through the top of the plunger 18, there being no attempt to make the rods and plunger top any tighter than enough to obstruct the flow of air sufficiently to carry out the objects of the pump.

On the top of the plunger there is the gasket or washer 20 which bears on the inside of the cylinder 12. The bottom of the plunger 18 is closed by means of the cap 21, which has the two inwardly opening valves 22, 23. The plunger is also provided with two large openings 24, above the level of the gasket 9. The plunger is reciprocated by means of two hollow rods 26, 27 which pass through stuffing boxes 28, 29 at the top of the cylinder 2. These two rods are connected to the periphery of the cylinder 18, and under normal operation, a sufficient quantity of air is forced through the rods 26, 27 to substantially fill the cylinder 12, and any loss of air by absorption is made up, from time to time, by pumping more air 90 through the pipes 26, 27 and allowing it to pass into the air-chamber through a tube 30, which has a very small opening therein, and through very small openings 31, 32 at the top of the pump plunger.

95 It will be seen that whatever may be the water pressure within the pump that an equivalent pressure will be brought to bear upon the air within the air-chamber above the plunger, and in the air chamber formed by the top of the plunger and the partition 15 in conjunction with the partition 15^a carried by the plunger itself.

100 In the operation the plunger will be raised and lowered its present position being such as to require it to be lowered. This will compress the air in the plunger chamber more than it is at the time when the pump starts to operate, and as the opening between the two chambers is very small, it 105 cannot quickly equalize, but will cause the plunger to operate as though it were operat-

ing between two heavily stressed springs with the result that any downward movement is met immediately thereafter by a tendency of the plunger to rise, and a slight upward movement of the plunger will cause it to rise above its point of rest, and this action will be repeated as long as power is applied to the pump, the two air chambers acting as buffers to cause the plunger to surge back and forth at each end of its stroke and deliver a steadier stream of water than is delivered from the ordinary reciprocating pump.

It is to be observed that in its present position the plunger is ready to move down to the end of its stroke, at which time the valves 4 and 5 will be closed. The valves 22, 23 will be open and the fluid will be forced upward through the openings 24.

It will be apparent to those skilled in the art that several of these cylinders may be coupled together and used in tandem if that is desired.

In Figure 5 there is shown a slightly modified form of the invention, in which the well casing is indicated at 40. This well casing may be of any form, and the pump casing is indicated at 41.

The pump casing has a fitting 42 at its lower end, which carries a pair of inwardly opening valves 43, 44, and the fitting 42 carries a suction pipe 45.

At a suitable place close to the valve 43, 44, there is a ring 46, secured within the pump casing 41 which carries a packing 47, which bears against the tube 48. This tube has a cap 49 at its lower end, and has two inwardly opening valves 50, 51, therein.

This tubular member is connected to another tubular member, or another series of tubular members by means of the coupling 52 at which coupling there is a partition 53 so that an air-tight chamber is formed in the upper portion of the tubular member 48, but it has holes 54 therein to permit the water pumped to be discharged from the tube 48.

A tube 55, of any suitable length, is connected to the coupling 52, and it has a hole 56 at its lower end adjacent the partition 53. At the upper end the tube 55 has a cap 57 through which a pipe 58 extends and which pipe also extends through the partition 53 at its lower end.

The cap 57 also has a pipe 59 connected therewith to supply the tube 55 with air, and the cap 57 is also connected by the link 60 with a suitable reciprocating arm 61 for the operation of the pump.

The tubing 48 and 55 is sufficiently light to allow the air that is placed within the tubing to counterbalance the weight of the entire body of reciprocating parts. This is accomplished by using light boiler tubing and a quantity of air is supplied to the chambers formed by the pipes 48 and 55 which will just balance their weights.

In operation, as the pump plunger is reciprocated, the water will fill the pipe 41 and run out the pipe 62. At the same time the pressure of water within the pipe 41 will be applied to the air within the tube 48 and within the tube 55 with the result that said air will be under the same pressure as the pressure of the column of water.

As the pump plunger is reciprocated, the air contained within said plunger will be subjected to varying pressures and this varying pressure will cause the water to surge in and out of the tube 48 and the tube 55 and cause a substantially uniform delivery of water from the pipe 62.

What I claim is as follows, but various modifications may be made in the construction shown in the drawings and above particularly described form, within the purview of my invention:

1. In a pump, the combination of the pump cylinder, a secondary cylinder inside the same, a hollow pump plunger movable within the second cylinder and within the outer cylinder, the secondary cylinder and pump plunger forming two air chambers for balancing the operation of the pump plunger and valves to allow the discharge of the fluid through the hollow pump plunger.

2. In a reciprocating pump, a pump cylinder, a hollow pump plunger therein, a second cylinder within which said plunger is also movable, and forming therewith a pair of air-chambers adapted to hold air at the pressure of the water being pumped to aid in reversing the pump plunger at each end of its stroke to deliver a steady stream of fluid.

3. In a reciprocating pump, a pump cylinder, a hollow pump plunger therein, a secondary cylinder within which the pump plunger operates and forming with it a pair of air chambers to hold the air at the pressure of the water being pumped to balance the pump plunger, and valves to allow the liquid being pumped to pass through the pump plunger.

In testimony whereof I have hereunto set my hand this 15th day of July A. D. 1922.

CHARLES O. HASKELL.
